REMOTE CONTROL HOUSING

Norbert T. Kuypers, Warren, Mich., assignor to Borg-Warner Corporation, Chicago, Ill., a corporation of Delaware

Filed Dec. 26, 1967, Ser. No. 9,933

Term of patent 14 years

Int. Cl. D13—03; D8—03
U.S. Cl. D26—13

FIG.3

FIG.1

FIG.2

FIG.4

FIG. 1 is a front elevation view of a remote control housing showing my new design;

FIG. 2 is a rear elevation view of the remote control housing;

FIG. 3 is a top plan view of the remote control housing; and

FIG. 4 is a side elevation view of the remote control housing.

The broken lines are for illustrative purposes only.

I claim:

The ornamental design for a remote control housing, substantially as shown and described.
